UNITED STATES PATENT OFFICE.

THOMAS C. CAMERON, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

DESIGN FOR A COMBINATION CORNICE AND PILASTER FOR STORE FURNITURE.

Application filed January 3, 1922. Serial No. 17. Term of patent 14 years.

To all whom it may concern:

Be it known that I, THOMAS C. CAMERON, a citizen of the United States, and a resident of the city of Grand Rapids, in the county of Kent and State of Michigan, have invented a new, original, and ornamental Design for Combination Cornice and Pilaster for Store Furniture, of which the following is a specification, reference being had to the accompanying drawing, forming a part thereof.

In the drawing,

Fig. 1 is a perspective view of the cornice

and pilaster made in accordance with my new design, the unit of store furniture to which it may be applied being shown in dotted lines, and

Fig. 2 is a fragmentary enlarged front elevation showing the cornice and pilaster design.

I claim:

The ornamental design for a combination cornice and pilaster for store furniture, substantially as shown.

THOMAS C. CAMERON.
